(57) **CLAIM**

The ornamental design for a mixing bowl, as shown and described.

DESCRIPTION

FIG. 1 is a top, right perspective view of a mixing bowl according to our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1; and,

FIG. 8 is a bottom, left perspective view of FIG. 1.

The stippling shown in the figures represents colored surface portions of the mixing bowl.

1 Claim, 6 Drawing Sheets
